CLAIM

The ornamental design for a bottle, as shown and described.

DESCRIPTION

FIG. 1 is a top perspective view of the bottle in accordance with our design;

FIG. 2 is a front elevational view of the bottle in accordance with our design;

FIG. 3 is a first side elevational view of the bottle in accordance with our design;

FIG. 4 is a back elevational view of the bottle in accordance with our design;

FIG. 5 is a second side elevational view of the bottle in accordance with our design;

FIG. 6 is a top end view of the bottle in accordance with our design; and,

FIG. 7 is a bottom end view of the bottle in accordance with our design.

The evenly broken lines illustrate parts of the article that form no part of the claim. The dash-dot-dash lines represent the boundaries of the claim and form no part thereof.
